UNITED STATES PATENT OFFICE.

GEORGE B. HOWELL, OF PHILADELPHIA, PENNSYLVANIA.

WATER-CLOSET.

SPECIFICATION forming part of Letters Patent No. 623,311, dated April 18, 1899.

Application filed December 5, 1898. Serial No. 698,265. (No model.)

To all whom it may concern:

Be it known that I, GEORGE B. HOWELL, a citizen of the United States, residing at Philadelphia, in the county of Philadelphia and State of Pennsylvania, have invented certain new and useful Improvements in Water-Closets; and I do hereby declare the following to be a full, clear, and exact description of the invention, such as will enable others skilled in the art to which it appertains to make and use the same.

The present invention relates to water-closets, and more particularly to the siphon type, although applicable to other types; and the chief object is to provide a compact and effective system of waterways for flushing the bowl and exhausting the siphon or hopper, as the case may be, the same to be supplied directly from a water-main, dispensing with an elevated tank such as ordinarily used with this type of closet—*i. e.*, a tank for each closet—it being understood that it is within the purview of my invention to utilize a water-supply from a large general supply-tank.

With the above-stated and other objects hereinafter made apparent in view the invention consists in a number of novel features of construction and combinations of parts, all of which are recited in the appended claims, and a preferred form of embodiment of which is specifically described hereinafter with reference to the accompanying drawings, forming part of this specification.

Of said drawings, Figure I represents the closet in perspective as viewed from the rear. Fig. II represents the same in cross-sectional rear elevation. Fig. III is a central longitudinal section. Fig. IV is a horizontal section taken on line IV IV of Fig. III. Fig. V is a central longitudinal section of a modified form of closet, and Fig. VI is a section taken substantially on line VI VI of Fig. V.

The bowl *a* is of well-known form, being made with an overhanging flushing-rim *a'*, and in the present instance the latter, in addition to having the usual discharge-holes in its under side, is formed with a number of holes *a''*, extending downwardly through its inner wall at an angle of forty-five degrees, so as to direct streams of water upon floating paper which might otherwise remain partially dry and fail to leave the bowl. The siphon

has its shorter limb *b* opening into the bottom of said bowl, while its longer limb *b'* stands vertically in rear of the latter and may have the usual sewer connection.

In the construction shown in Figs. I to IV the substantially triangular space between the limbs of the siphon is closed by side webs *b²*, having circular openings, around which are formed cylinders *c*, standing out from said webs. Waterways *d* and *e* open out of the upper sides of said cylinders, respectively, and extend vertically along the side webs and the sides of the siphon, the waterway *d* being formed with a forward bend at its upper end and united with the flushing-rim, with which it communicates by the port *d'*, while the waterway *e* is given an inward and slightly-rearward bend at the top, whereby it is carried over the dome of the siphon and above the longer limb thereof, with which it communicates through a jet opening or port *e'*.

The structure thus far described is of earthenware and produced by well-known methods. A metallic pipe *f* passes through the cylinders *c* and the space between the siphon-limbs, said pipe having an annular flange *f'* taking over the end of one cylinder and a screw-threaded end portion protruding beyond the other cylinder and receiving a cap-nut *f²*. Gaskets *g* are interposed between the cylinders and the flange and cap-nut, and when the latter is screwed home it will be apparent that water-tight closures are made between the metal pipe and the earthenware structure. The said pipe is formed in its upper side with ports *d''* and *e''*, communicating, respectively, with the waterways *d* and *e*, and in its front side at the middle with a port *j* in registry with a port *j'*, made through a thickened portion of the rear wall of the bowl, and beyond its flange the pipe is contracted somewhat and unites with a valve-casing *h*, having on one side a screw-threaded nipple *h'*, whereby a connection is effected with a water-main or water-supply conduit. A valve structure of an appropriate type is arranged within said casing to properly control the water-supply, the valve-stem being designated by the letter *i* and being jointed to one end of a lever *i'*, which is pivoted intermediate of its length to a bracket *i''* on the casing and is equipped at the forward end

with a handle i^3 and a weight i^4 to normally close the valve. A pull upwardly upon the said handle will open the valve and water will immediately rush into the pipe f and thence up the waterways d and e , one stream discharging into the flushing-rim and the other into the dome of the siphon, the result being that siphonic action is set up to exhaust the contents of the bowl while the latter is being flushed from the rim by the other stream of water. It will of course be understood that water stands normally in the bowl to the height of the short limb of the siphon, effecting a seal, and when the discharge has ceased a diminished supply of water through the flushing-rim reestablishes such seal.

The establishment of the seal in the bowl insures a similar seal in the waterways d and e , for the reason that the small ports j and j' afford communication between the bowl and the pipe f , the object of providing said ports being to accomplish this result, which is important, as the absence of a water seal in said ways would permit escape of sewer odors through the rim of the bowl.

In the construction shown in Figs. V and VI, the rear limb b'' of the siphon is not formed in connection with a horizontal sewer-conduit in the earthenware structure, as before, but terminates some distance above the base-plane of the latter, and a swivel connection is effected between the same and a horizontally-extending metallic pipe k , so a discharge can be had in any direction desired. Said metallic pipe is formed with an upward-opening bell k' , embracing the siphon-limb and formed with an outstanding flange k^2 , against the underside of which fits a flat ring m , apertured at intervals to receive clamping-bolts m' . These bolts extend through apertures in the flange m^2 of a ring m^3 , surrounding the siphon-limb and cupped to receive a rubber gasket m^4 , against which the flange k^2 of the bell k' abuts. By turning up nuts m^5 on the bolts m' below the ring m the gasket m^4 will be forced into intimate contact with the siphon-limb in an obvious manner and a water-tight joint will be made. Upon loosening the clamping devices the pipe can be swung in a horizontal plane to any desired position and again clamped to the siphon-limb, this pipe being preferably formed with a lug k'' to rest upon the surface above which the pipe extends. This construction of closet is particularly adapted to marine use, but may of course be utilized in other connections. In this modified form of closet there are no side webs closing the space between the limbs of the siphon, and consequently an earthenware cylinder c' extends through such space to accommodate the metal pipe f , such cylinder being integral with the rest of the earthenware structure and ported, as shown at d^2 and e^2 , for communication with the waterways d and e and as shown at j'' for registry with the port j in the metal pipe.

The waterway d , instead of opening di-

rectly into the flushing-rim, is shown in Fig. V as opening into a refilling-chamber n , formed between said rim and communicating by a port n' with the latter and by a smaller port n^2 with the bowl. The port n' being at the top of the chamber the latter fills before the water flows to the rim, and thus a supply of water is retained, which eventually escaping through the small port n^2 at the bottom of the chamber insures the refilling of the bowl to the proper height after each action of the siphon.

It will be seen that either of the above-described constructions is well calculated to thoroughly fulfil the object primarily stated in addition to others herein stated; but at the same time it is to be understood that the invention is capable of embodiment in other forms than that here shown.

Having thus fully described my invention, what I claim as new, and desire to secure by Letters Patent, is as follows:

1. In a water-closet, the combination of a bowl having a flushing-rim, a siphon, a horizontal water-pipe extending between the limbs of the siphon and having a supply connection at one end and ports in its upper side on opposite sides of the siphon; and waterways communicating with said ports respectively, one of said waterways leading to the dome of the siphon and the other to the flushing-rim, substantially as and for the purpose described.

2. In a water-closet, the combination of a bowl having a flushing-rim, a siphon whose short limb opens into the bottom of the bowl and whose long limb is in rear of the same, webs closing the space between the siphon-limbs, waterways extending vertically along opposite sides of the siphon structure, one opening into the flushing-rim and the other opening into the dome of the siphon, a horizontal water-pipe extending transversely between the limbs of the siphon and through the side webs, said pipe having ports communicating with the waterways, respectively and a valved water-supply connection for one end of said pipe.

3. In a water-closet, the combination of a bowl having a flushing-rim, a siphon whose short limb opens into the bottom of the bowl and whose long limb is in rear of the same, webs closing the space between the siphon-limbs, cylinders outstanding from said webs, waterways extending vertically from said cylinders respectively and along the webs, one of said ways opening into the flushing-rim and the other into the dome of the siphon, a water-pipe extending through the cylinders, the webs and the space between the siphon-limbs, and having ports communicating respectively with the waterways, and a valved water-supply connection for said pipe.

4. In a water-closet, the combination of a bowl having a flushing-rim, a horizontal water-conduit extending transversely behind the bowl, and communicating at one end with

a water-supply, and having a port in its upper side and a waterway extending upwardly from the said port on one side of the bowl and communicating with the flushing-rim.

5 5. In a water-closet, the combination of a bowl having a flushing-rim, a siphon, a water-conduit extending transversely behind the bowl and communicating with the lower part thereof and also with a water-supply, 10 and waterways leading from said conduit on opposite sides of the bowl and communicating with the flushing-rim and siphon respectively.

6. In a water-closet, the combination of a 15 bowl having a flushing-rim, a siphon, a wa-

ter-conduit extending transversely between the limbs of the siphon and communicating with a water-supply and having a port whereby communication is established with the lower portion of the bowl, and waterways 20 leading upwardly from the said conduit on opposite sides of the siphon and communicating respectively with the flushing-rim and the long limb of the siphon.

In testimony whereof I affix my signature 25 in presence of two witnesses.

GEO. B. HOWELL.
